(57) CLAIM

The ornamental design for a retractable sunshade for car windshield, as shown and described.

DESCRIPTION

FIG. 1 is a front perspective view of a retractable sunshade for car windshield, showing my new design;

FIG. 2 is a rear perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof;

FIG. 8 is a bottom plan view thereof;

FIG. 9 is a partial enlarged view of FIG. 1;

FIG. 10 is a partial enlarged view of FIG. 1;

FIG. 11 is a partial enlarged view of FIG. 1;

FIG. 12 is a partial enlarged view of FIG. 1;

FIG. 13 is a partial enlarged view of FIG. 1;

FIG. 14 is a partial enlarged view of FIG. 1;

FIG. 15 is a partial enlarged view of FIG. 2;

FIG. 16 is a partial enlarged view of FIG. 2;

FIG. 17 is a partial enlarged view of FIG. 2;

FIG. 18 is a partial enlarged view of FIG. 2;

FIG. 19 is a partial enlarged view of FIG. 3;

FIG. 20 is a partial enlarged view of FIG. 3;

FIG. 21 is a partial enlarged view of FIG. 3;

FIG. 22 is a partial enlarged view of FIG. 3;

FIG. 23 is a partial enlarged view of FIG. 4;

FIG. 24 is a partial enlarged view of FIG. 4;

FIG. 25 is a partial enlarged view of FIG. 4;

FIG. 26 is a partial enlarged view of FIG. 4;

FIG. 27 is a partial enlarged view of FIG. 5;

FIG. 28 is a partial enlarged view of FIG. 6;

FIG. 29 is a partial enlarged view of FIG. 7;

FIG. 30 is a partial enlarged view of FIG. 7;

FIG. 31 is a partial enlarged view of FIG. 7;

FIG. 32 is a partial enlarged view of FIG. 7;

FIG. 33 is a partial enlarged view of FIG. 8;

(Continued)

FIG. 34 is a partial enlarged view of FIG. 8;

(56)

References Cited

FIG. 35 is a partial enlarged view of FIG. 8; and,
FIG. 36 is a partial enlarged view of FIG. 8.

The dashed broken lines in the figures are for the purpose of illustrating portions of the retractable sunshade for car windshield, which form no part of the claimed design. The dot-dash broken lines in the figures are for the purpose of illustrating the periphery of the enlarged views and form no part of the claimed design.
